(57) CLAIM

The ornamental design for a dual screen computer interface, as shown and described.

DESCRIPTION

FIG. 1 is a plan view of the dual screen computer interface showing my new design;

FIG. 2 is a plan view showing a variant of FIG. 1 illustrating the interface devices; and,

FIG. 3 is a perspective view of the variant of FIG. 2.

1 Claim, 3 Drawing Sheets

FIG. 1

FIG. 2

FIG. 3
